UNITED STATES PATENT OFFICE.

BENJAMIN FURNEY LLOYD, OF CHERRY GARDENS, SOUTH AUSTRALIA,
AUSTRALIA.

BOOT AND SHOE CLEANING AND POLISHING MACHINE.

No. 813,904.

Specification of Letters Patent.

Patented Feb. 27, 1906.

Application filed August 11, 1904. Serial No. 220,357.

To all whom it may concern:

Be it known that I, BENJAMIN FURNEY LLOYD, vigneron, a subject of the King of Great Britain and Ireland, residing at Cherry 5 Gardens, in the State of South Australia, Commonwealth of Australia, have invented a certain new and useful Boot and Shoe Cleaning and Polishing Machine, of which the following is a specification.

10 This invention comprises a machine for cleaning and polishing boots and shoes; and it consists of a suitable bed carrying a reciprocating frame provided with brushes and a movable slide.

15 The reciprocating frame carries brushes arranged, preferably, in three pairs of special form and attachment and is connected to a crank disk or handle, whereby it is reciprocated. Of the brushes the first pair removes 20 the dirt, the second pair applies the blacking, and the third pair polishes the boots. The movable slide is fitted with lasts of spring-steel wire, upon which the boots are fitted, and so passed between the several pairs of 25 brushes. The blacking-supply is preferably mounted upon the reciprocating frame.

30 In order that my invention may be clearly understood, I will describe the same with reference to the accompanying drawings, in which—

Figure 1 is a perspective view of the machine complete. Fig. 2 is a cross-section at about line *a b* of Fig. 1. Fig. 3 is a plan view of the reciprocating frame with brushes. Fig. 4 is a side view of the movable slide. The 35 slide is shown divided into three parts hinged together. Fig. 5 represents one of the parts of the slide partly in section to show the method of holding the spring-last. Fig. 6 shows one of the brushes with its bridge-piece and projecting pins. Fig. 7 is a detail view 40 illustrating the connection between a brush and the reciprocating frame. Fig. 8 is a detail sectional view of the toe-piece of the last.

45 The bed (A illustrated in the drawings) is constructed of wood and consists of a rectangular frame, with a longitudinal piece running down the center. The upper portion of such longitudinal piece has a central dovetail groove which carries the movable slide B. At each side of the central dovetail groove is a bar C of inverted-V shape, the two bars 50 forming runners for a reciprocating frame formed of two boards D D, connected together

by arch-shaped metal stays E E, the bottoms 55 of which are shaped to rest upon and embrace the aforesaid runners, as shown more particularly in Fig. 2.

The reciprocating frame is moved backward and forward by means of a crank-handle F and disk with eccentric-pin, the pin being connected to a suitable point on the frame by a rod G. The axle of the crank-handle and disk is supported in a wide bearing H, attached to the table or bed. The length of 60 movement of the frame is preferably about eight inches from end to end.

Upon the inside of the two boards D D of the reciprocating frame are secured the brushes K K, arranged in three pairs. The 70 brushes are made of concave shape, and they are fixed to the boards in such a way that they operate upon every part of the sides, back, and front of the boots. The method of fixing is shown more particularly in Figs. 75 3 and 6 and is as follows: To the back of the brush is secured a bridge-piece L, in the center of which is a hole, through which passes the reduced end or point of a thumb-screw M. The thumb-screw is retained therein by being 80 upset or by other means, the connection being loose, as shown in Fig. 7, so that the brush can oscillate upon the screw-point. The screw engages a thread in the board D, and on being rotated the brush is moved toward 85 or from the board. Near each end of the brush is a long pin N, which passes through an elongated opening in the board D, so that the brush can rock upon the central screw. A spiral spring O is fitted upon each of the 90 pins N between the bridge-piece L and the board D to make the brushes more sensitive in their movement. The springs O render the brushes more sensitive in their movement, owing to the fact that when one end of the 95 brush is forced backward the spring at that end is compressed, while the spring at the other end is allowed to expand, (see Fig. 7,) and the tendency of the compressed spring is to throw the brush back immediately the boot 100 is removed from that end. As the brushes are moved back and forth upon the boots the brushes rock upon the ends of the central screws, and the two springs being of equal power tend to keep the brushes straight and 105 return them to a straight position after displacement. This mode of fixing the brushes allows them to be opened apart or closed to

gether to suit the size of boot and also allows them to work round the heel and toe as the frame is reciprocated.

The blacking is carried in a vessel *P*, 5 mounted upon the reciprocating frame over the central pair of brushes, and is provided with pipes *p*, from which the blacking drips upon the brushes, one pipe discharging over the heel portion and one over the toe portion 10 of the brushes.

The boots are carried upon spring-steel lasts *Q*, fitted upon the central slide *B*, which slide is preferably divided into three parts connected together by hinges, so that the 15 end parts may be turned upward, if necessary, when clear of the dovetail groove before described. If preferred, however, the hinges may be omitted and each last may be carried by a separate short slide, as shown in Fig. 5.

20 Each of the lasts is constructed of spring-steel wire, fitted with a heel-piece *R* and a toe-piece *S*, as shown in Fig. 5, in which the boot is shown in dotted lines only. The heel-piece is solid, but the toe-piece, as shown 25 in Fig. 8, is formed of two wings hinged together and fitted with springs beneath, which allow the wings to be closed when a boot is being placed on or taken off, but spread them when the boot is in place for cleaning. The 30 last is fitted into the slide by means of a pin *V* and tongue *W*, key-fashion, the pin fitting into a vertical hole and the tongue engaging a socket, as shown in Fig. 5. To enter the last, it is turned with the boot to the rear and 35 the pin and tongue dropped into place in the socket. The last is then turned to the front, the tongue moving into its socket and the toe of the boot resting upon the wedge or block *T* on the slide. The boots are placed on the 40 spring-last before the last is secured on the slide.

In using my machine the boots are placed upon the spring-lasts, the lasts secured in the slide, and the slide entered in the dovetail 45 groove. The reciprocating frame is then operated by the handle moving the brushes back and forth upon the boots. The first pair take the dirt off, the second spread the blacking evenly over the whole surface, and 50 the third polish the boots. Three boots are operated on at the one time and as one boot is finished the slide is moved on and another boot operated upon. It is convenient to have several slides to each machine.

55 Having now fully described and ascertained my said invention and in what manner the same is to be performed, I declare that what I claim is—

1. In a boot cleaning and polishing machine, a reciprocating frame comprising two

longitudinal members connected together by stays, stationary runners upon which the bottom portions of said stays slide, the said runners being supported by a suitable bed, brushes carried by said longitudinal members and arranged in pairs, thumb-screws for adjustably attaching the brushes to the longitudinal members so that the brushes can be moved in and out bodily to accommodate various sized boots, the connection between 65 the screws and the brushes being loose so that the brushes may rock upon the screws to operate upon the back and front of the boots substantially as described and for the purpose set forth. 70

2. In a boot cleaning and polishing machine the combination with a reciprocating frame of brushes arranged in pairs and each having a concave face, and means for flexibly securing the brushes to the frame, the said 80 means comprising a bridge-piece on the back of each brush, and a thumb-screw at the center of the bridge-piece, and securing it to the frame, the bridge-piece having a long pin at each end passing through a slot-opening in 85 the frame substantially as described and for the purpose set forth.

3. In a boot cleaning and polishing machine the combination of a reciprocating frame, concave-faced brushes arranged in 90 pairs, bridge-pieces secured to the backs of the brushes, one to each brush, thumb-screws attached at their points to the bridge-pieces and having their screw-threads engaging screw-threads in the frame, pins projecting from each end of the bridge-pieces to and 95 through slot-openings in the frame, and spiral springs mounted upon the said pins between the bridge-piece and the frame, all substantially as described and for the purpose 100 set forth.

4. In a boot and shoe cleaning and polishing machine, a reciprocating frame comprising two longitudinal members, arch-shaped metal stays connecting said members, stationary bars on which the lower ends of said stays are fitted to slide, brushes arranged in pairs, thumb-screws adjustable in the said longitudinal members, the said brushes being mounted to rock on the inner ends of said 110 screws, and means for maintaining the brushes in an approximately horizontal position, substantially as described.

In witness whereof I have hereunto signed my name, this 1st day of July, A. D. 1904, in 115 the presence of two subscribing witnesses.

BENJAMIN FURNEY LLOYD.
